UNITED STATES PATENT OFFICE.

UPTON H. BALSLEY, OF PHILADELPHIA, PENNSYLVANIA.

TELEPHONE APPARATUS.

SPECIFICATION forming part of Letters Patent No. 394,951, dated December 25, 1888.

Application filed August 2, 1888. Serial No. 281,712. (No model.)

To all whom it may concern:

Be it known that I, UPTON H. BALSLEY, of the city and county of Philadelphia, and State of Pennsylvania, have invented an Improvement 5 in Telephonic Apparatus, of which the following is a specification.

My invention has reference to telephone-circuits adapted to central-station purposes; and it consists in certain improvements, all 10 of which are fully set forth in the following specification, and shown in the accompanying drawings, which form part thereof.

The object of my invention is to simplify the general construction and arrangement of 15 circuits adapted to central-station work in telephony, and more particularly to greatly increase the efficiency of the apparatus over those now in use, whereby far less space is required and the capacity of the operator to 20 handle the switches is very largely improved.

The great advantages of my improvements may not be very apparent in small central-station work; but where the number of subscribers is from five hundred to ten thousand, 25 then the decided advantages will be clearly apparent.

My invention, therefore, is especially adapted to large central-station work.

In carrying out my improvements I can dispense entirely with the drops found so necessary in many other systems, and by so dispensing with them the available space or area adapted to switch-board purposes is largely increased, making it possible to place within 35 operative reach of an operator many more subscribers than was heretofore found possible, and at the same time trunk-lines and other objectionable features now in use are dispensed with; but it is manifest that my 40 invention may also be used in connection with drops whenever it is found expedient to employ them, as in the case of distant subscribers. The general plan of the circuits for calling for connections or those at the 45 subscriber's office is substantially the same as now in use in work employing what is known as the "Law system." My switch-board is in a few particulars somewhat similar to those now in use; but in operation it 50 differs very materially.

By my improvements I am enabled at but trifling expense to convert the majority of the

large central stations in workable apparatus with a greatly-increased list of subscribers and with less space necessary and less labor 55 on the part of the employés in the central station.

Many of the central-station plants now in use in our large cities are working at their maximum capacity and under great difficulties. By my improvements I greatly increase 60 the capacity without requiring more space and greatly reduce the operators' labor.

In the drawings, Figure 1 is a diagrammatic view illustrating the construction and 65 arrangement of parts and circuits constituting my improvements as applied to complete metallic circuits for the subscribers. Fig. 2 is a similar view of same as used upon single-wire circuits between subscribers and employing the ground as the return; and Fig. 3 70 is a sectional elevation of one of the switch-plugs.

First referring to the closed or metallic circuit system, as shown in Fig. 1, we have at 75 the lower part of the figure the central-station apparatus, and at the upper part the subscriber's apparatus, and which may be substantially the same as now in use. The central station is provided with the switch-board 80 A, having the plug-tubes B arranged close together and formed of metal. Immediately in the rear of each of these tubes B is a spring-switch, C, normally resting against a contact, D. When a plug, H, such as shown 85 in Fig. 3, is inserted into the tube B, the metallic head J presses the switch C to one side and breaks contact with D, and simultaneously the outer metal cylinder, h, of the plug makes contact with the tube B, thus breaking 90 one contact and making another. The head J and its extension are supported in a fixed relation to the cylinder h of the plug H by the insulating medium I. These plugs may be of any other suitable construction, 95 they at best being simply special forms of switches requiring but little superficial space. As shown, there are three sets of these switches, B C D—that is to say, there are two other switches, C D, which are connected by 100 circuits E and F with the primary or first switch, connecting with the line P leading to the subscriber, and connection may be made with said subscriber by inserting a plug in

either of these latter switches (in other switch-boards) in place of the first. The object of this is that each operator can attend to a given number of subscribers, and while having control of the wires of particular subscribers 5 he can connect them with any of the other subscribers. Thus an operator at switch-board No. 1 can connect his subscribers with each other or with any of the other subscribers whose lines would terminate in the switch-board of the duplicate or triplicate switches shown, and one set of such switches would be within reach of operator at No. 1. An operator at No. 2 switch-board 10 would in like manner be able to connect his subscribers with each other or with subscribers from No. 1 or No. 3 switch-boards. This gives each operator full range of all subscribers. All the subscribers on the call-circuit 15 of any operator are considered as his subscribers, and would be said to be the subscribers of his switch-board. If the operator at No. 1 switch-board inserts a plug in the first switch, it is apparent that contact at D 20 is severed and that every switch in the entire central station at the other switch-boards corresponding to this subscriber is cut out and he cannot be interrupted by duplicate connection. After connection of all of the 25 switches C D of all of the switch-boards corresponding to one operator, the contacts D thereof are connected by wires G together and connect with the call-line T, having the operator's telephone U, and extending out 30 into the city and connecting with the subscribers of the operator to whom the receiver U corresponds.

As shown in Fig. 1, the telephone U belongs to the subscriber at switch-board No. 1, and 35 line T would connect with the subscriber on circuits P, P', and P². Lines P P' P² are line-wires leading to different subscribers, the apparatus of one of which subscribers alone being shown. The number of subscribers on such a wire in the construction shown in Fig. 2 would be inverse proportionally to the duty required of it. The return-wire m from the subscriber connects the tube B of the switch C D connecting with the 40 line P leading to this subscriber, and all of the corresponding tubes, B, of the respective switch-boards Nos. 2 and 3 are connected, as shown, by wires O. In like manner the other tubes are connected by wires O' and O², so 45 that a contact at one switch-board will connect with all corresponding tubes at the other switch-boards.

Connection is made by the operator by 50 means of two plugs, H H, having their heads J J connected by a flexible circuit, K', and their tubular parts h connected by flexible circuits K to switches k k, adapted to contact with an alarm or call circuit, L, containing a battery, l, or other source of electric power, 55 the other end of which is grounded. The switches k k when released close a circuit, k', by back-stops, so as to couple the tubular parts

h h of the plugs. The operator at any switch-board would have sufficient of the plugs H as to make all connections which could be called 70 for. For simplicity, I have shown but one set of said switch-plugs.

The operation will now be understood. The subscriber lifts his receiver N off the lever M, shifts the switch Q, and calls for connection 75 with, say, the subscriber of wire P². The induced current would pass from induction-coil of the local battery of the calling subscriber by R Q q P C D E C D F C D G T, operator's receiver U T t q Q R N, to induction-coil 80 of local battery again. Having made his wants known, the subscriber waits for the signal that the connection is made. The operator places the switch-plugs H H into the holes or tubes B, corresponding to lines P and P², and this 85 breaks switch C D of each of said circuits and connects B B of said circuits by tubular parts h, wires K, and circuit k' of switches k. It also connects the switches C C of P and P² through heads J of the plugs and wires K'. 90 When this is done, the operator temporarily presses strongly the lever k to call up that subscriber on line P², and presses for an instant upon switch k, corresponding to the subscriber on line P, to indicate that the connection is 95 made, the signal given to the calling subscriber being a tap. Current on signaling the subscriber being called up passes by ground-battery l L k K h of H B, line m, bell-magnets O, wire m', through switch-contacts M M' to 100 ground. The two subscribers are now coupled, and the switch Q is shifted. The induced current from local battery and induction-coil passes, by wire R, switch r, switch Q, line P, to 105 C, plug-head J, wire K' to other plug-head, J, to C, and to line P² to other subscriber, returning by wire m of P² subscriber to O² to tube B, thence by plugs, cylinders h, and wire K to tube B of subscriber on P line shown, and by m, bell O, contact M² to r, through switch Q 110 to R, to receiver N, and to induction-coil of transmitter. When the subscribers are not using the instruments, the receiver is hung upon the switch-lever M, and is drawn down, making contact with ground by switch M', 115 and as the lever M is connected with the armature of the bell by wire m' and wire circuit m is broken at M² M³ the operator, in calling up, would send the current by wire m, magnets O, through back contact of the armature of bell, by wire m' to lever M and by switch M' to ground. In this case the bell is 120 a vibrator, ringing rapidly. When the subscriber is calling up and has the receiver N down, then m' is out of circuit, and the electric bell is converted into a stroke-bell, requiring the operator to interrupt the circuit to make it strike. By this means a distinctive signal may be given to the calling subscriber if the subscriber's line he calls for is 125 busy. In this latter case the current passes through m O, contacts M² M³ to contact r, and by wire S to ground. One of the particular features which makes this invention so ad-

vantageous is that the receiver of the operator of any switch-board is in circuit with every switch of his subscribers, whether they be on his board or on the boards of all other 5 operators, and such switches are not in circuit with the receivers of any other operator, and, further, that when any other operator has cut out one of the subscribers first mentioned by connection then the receiver of the 10 first-mentioned operator is cut out of circuit with said subscriber.

Referring now to Fig. 2, which shows the arrangement of my improvement as applied to a metallic outgoing circuit with a ground 15 return. In this arrangement there is no metallic circuit *m*. The arrangement at the central station is in all material respects the same as in the case of the metallic-circuit system shown in Fig. 1. The signal-circuit *T* in this 20 case is preferably looped, as shown, forming two paths for the current from the subscribers, and thus making the system doubly sure in its operation. The apparatus at the subscriber's office is shown in the upper part of Fig. 2, and 25 the connections are made as follows: The line-wire *P* connects with the bell-magnets *O*, and through the back-stop connects by the wire *m'* with the receiver-lever *M*, and this receiver-lever through the contact *M'* connects with 30 the ground, or when the receiver is removed for use it is connected with the receiver-circuit *R*, which, after passing through the induction-coil of the transmitter *n*, passes to the switch *Q'*, and by *S'* to ground. It will thus 35 be seen that if the operator at the central station wishes to signal the subscriber he simply inserts the plug *H* (in this case one metallic piece) into the proper tube *B* and presses the contact-switch *k*. This sends the current from 40 the battery *l*, through *K'*, head *J*, contact *C*, line *P*, signal *O*, circuit *m'*, contact *M'*, to ground. Upon inserting another plug, *H*, as shown, the said subscriber so signaled may be coupled with the subscriber on *P'* circuit, and 45 both subscribers will then be coupled through central station by wire *K'*, circuit *k'*, of back-stops of levers *k*, and their other connection will be through the ground.

When the subscriber wishes to signal the 50 central station for connection, he presses the switch *Q'*, so as to connect the circuit *R* with branch wire *T*, connecting with the main central-station circuit, and simultaneously therewith he removes the receiver, which closes the 55 circuit from the line *P* through *O m'*, switch lever *M*, to *R*. This will connect the subscriber in complete metallic circuit with the central-station operator, and at the same time cut out the ground-circuit formerly made by 60 switch *M'*. The operator is then informed through the metallic circuit with whom the subscriber desires to be coupled.

It is evident that the circuits at the subscribers' office in Fig. 2 may be arranged substantially similar to those shown in Fig. 1, as

the particular arrangement of the subscriber's local apparatus is of secondary importance.

The employment of a double call-circuit, *T*, is very important, as it gives to the operator two ways of signaling up the central operator, and it is inexpensive, as it may extend in all directions and return to central station, having subscribers throughout its entire length.

The circuits *O O' O'* in Fig. 2 are simply 75 test-circuits to enable an operator at Nos. 2 or 3 switch-board to ascertain if any subscriber at No. 1 switch-board is talking. In the case of Fig. 1 these circuits perform the double duty of test-circuits and line-circuits 80 by connection with circuits *m*.

It is evident that the minor details of my invention may be modified in numerous ways, well known to electrical engineers, without in the least departing from the spirit of my invention.

Having now described my invention, what I claim as new, and desire to secure by Letters Patent, is—

1. In central-station apparatus for telephony, the combination of two or more switch-boards corresponding to different operators, switches in each of said switch-boards, corresponding in number to all of the subscribers of the central station and normally in electric connection with the subscribers' lines, normally connecting circuits between all of the switches of all of the switch-boards which correspond to the same subscriber, a call-circuit for each switch-board connecting with its 90 subscribers and electrically connected with the connecting-circuits of said subscribers' switches, a receiver in each of said call-circuits close to the switch-board, a signal-battery or source of electric power, switch-plugs 95 or equivalent devices for connecting different subscribers, and switches for connecting the battery or source of electric power with the subscribers' circuits.

2. In central-station apparatus for telephony, the combination of two or more switch-boards corresponding to different operators, switches in each of said switch-boards, corresponding in number to all of the subscribers of the central station and normally in electric connection with the subscribers' lines, normally connecting circuits between all of the switches of all of the switch-boards which correspond to the same subscriber, a call-circuit for each switch-board connecting with its 110 subscribers and electrically connected with the connecting-circuits of said subscribers' switches, a receiver in each of said call-circuits close to the switch-board tubes or contact parts in line with each of the switches of 115 the subscribers, connecting-circuits between the subscribers and each of the tubes or contact parts of all of the switch-boards corresponding to each of said subscribers, a signal-battery or source of electric power, switch- 120

battery or source of electric power, switch- 125

plugs or equivalent devices for connecting different subscribers through the contacts and switches of the switch-boards, and switches for connecting the battery or source of electric power with the subscribers' circuits.

3. In a telephonic central station, the combination of a series of switch-boards, each of which has switches corresponding to all of the subscribers of the central station, circuits connecting each of the switches corresponding to one subscriber and in which all of the said circuits corresponding to the subscribers of one switch-board are connected, a call-circuit connecting with said circuits, an operator's receiver in said call-circuit, a series of subscribers' circuits connecting with the switches of the switch-board, to which the operator's receiver corresponds, and circuit connecting and breaking switch-plugs or equivalent devices to connect two subscribers and interrupt the circuits in the switch-boards of the subscribers so coupled beyond the point of coupling up.

4. In a telephonic station, the combination of a series of switch-boards, each having a number of subscribers controlling separate operators, switches C D for each subscriber and connected with the line-wires, connecting-circuits E F G, connecting each of the corresponding switches of each switch-board in series, a call-circuit, T, connected with the circuits E, F, and G, corresponding to the subscribers of one switch-board, an operator's receiver in said call-circuit, and suitable devices for breaking any of the switches C D and simultaneously coupling the corresponding subscribers' circuits connecting with the parts C of said switches.

5. In a telephonic central station, the combination of a series of switch-boards, each having a number of subscribers controlling separate operators, switches C D for each subscriber and connected with the line-wires, connecting-circuits E F G, connecting each of the corresponding switches of each switch-board in series, a call-circuit, T, normally connected with the circuits E, F, and G, corresponding to the subscribers of one switch-board, an operator's receiver in said call-circuit, contacts B, arranged in front of the switches C D, line-circuits m, leading from the various subscribers and connecting with the corresponding contacts, B, of all the switch-boards, and plugs H H, having heads to simultaneously break the circuits at C D, to connect two subscribers' circuits terminating in parts C, and to connect two subscribers' circuits m, terminating in two contacts B.

6. In a telephonic central station, a series

of switch-boards each having switches connecting with all of the subscribers of the station, connecting-circuits between all of the switches corresponding to each subscriber, a call-circuit from the operator of each switch-board at the central station to the subscribers of said switch-board, a receiver in said call-circuit, and circuit-breakers under the control of the operator of each switch-board to cut out any subscriber of another switch-board from connection beyond said operator and also to cut out the attending operator of the subscriber.

7. In a telephonic central-station system, the combination of a series of subscribers, two switch-boards having switches corresponding in number to all of the subscribers' connecting-circuits, and circuit-coupling devices for connecting two subscribers in circuit, a call-circuit for each of said switch-boards, each including a portion of the subscribers and both including all of the subscribers, and each connecting with all of the switches of their respective switch-boards, and a telephonic receiver in each of said call-circuits close to the switch-boards for the operator's use.

8. The combination of a series of subscribers, a looped metallic call-circuit leading from a central station and in connection with the various subscribers, line-circuits leading from the central station to the subscribers, an operator's receiver for said subscribers' line-circuits, connecting-circuits including the receiver between the looped call-circuit and each of the line-circuits of the subscribers, a signal or alarm for each of the subscribers normally in circuit with the looped call-circuit, and switches at the central station for coupling into operative circuit two subscribers' line-circuits independently of the looped call-circuit.

9. A looped metallic call-circuit, two subscribers' speech - transmitting instruments connected with the looped call-circuit, a central station, an operator's receiver in circuit with the looped call-circuit, and connecting-circuits between the speech-transmitting instruments of the two subscribers independent of the looped call-circuit, whereby they may be coupled for conversation and the looped call-circuit used for signaling only.

In testimony of which invention I hereunto set my hand.

UPTON H. BALSLEY.
